Des. 229,295
Patented Nov. 20, 1973

229,295

CURTAIN RUNNER

Kiyotsune Miki, 73, 1-chome, Higashi-kagaya-cho,
Sumiyoshi-ku, Osaka, Japan

Filed Oct. 14, 1971, Ser. No. 189,493

Term of patent 14 years

Int. Cl. D8—08

U.S. Cl. D8—248

FIG. 1

FIG. 2

FIG. 3

FIG. 4

FIG. 5

FIG. 1 is a perspective view of a curtain runner embodying my design.

FIG. 2 is a front view.

FIG. 3 is a right side view.

FIG. 4 is a plan view.

FIG. 5 is a bottom view.

Since the left side view is identical with the right it is omitted.

Since the rear view is identical with the front it is omitted.

I claim:

The ornamental design for a curtain runner, as shown.
